(57) **CLAIM**

The ornamental design for an LED light tube, as shown and described.

DESCRIPTION

FIG. 1 is a perspective view of an LED light tube showing my new design according to one embodiment;

FIG. 2 is a top plan view of the LED light tube of FIG. 1;
FIG. 3 is a bottom plan view of the LED light tube of FIG. 1;
FIG. 4 is a front elevational view of the LED light tube of FIG. 1;

FIG. 5 is a rear elevational view of the LED light tube of FIG. 1;

FIG. 6 is a right side elevational view of the LED light tube of FIG. 1;

FIG. 7 is a left side elevational view of the LED light tube of FIG. 1;

FIG. 8 is a perspective view of an LED light tube showing my new design according to another embodiment;

FIG. 9 is a top plan view of the LED light tube of FIG. 8;
FIG. 10 is a bottom plan view of the LED light tube of FIG. 8;
FIG. 11 is a front elevational view of the LED light tube of FIG. 8;

FIG. 12 is a rear elevational view of the LED light tube of FIG. 8;

FIG. 13 is a right side elevational view of the LED light tube of FIG. 8; and,

FIG. 14 is a left side elevational view of the LED light tube of FIG. 8.

The shade lines show contour and not surface ornamentation.
The broken lines are environmental and form no part of the claimed design.
